UNITED STATES PATENT OFFICE.

HERMAN T. REGNELL, OF ATTLEBOROUGH, MASSACHUSETTS.

DESIGN FOR A WATCH-CHARM.

SPECIFICATION forming part of Design No. 13,391, dated October 31, 1882.

Application filed September 25, 1882. Term of patent 7 years.

To all whom it may concern:

Be it known that I, HERMAN T. REGNELL, of Attleborough, in the county of Bristol and State of Massachusetts, have invented a new and original Design for Watch-Charms; and I do hereby declare that the following specification, taken in connection with the accompanying drawing, forming a part of the same, is a full, clear, and exact description thereof.

10 The design which is the subject of this invention relates to articles of jewelry; and it consists of a pendent charm for chains, which is composed of parts representing a miniature lamp-body, a chimney, and a shade, and of two 15 arms or wings in the form of scrolls of leaves, as will hereinafter appear.

In the illustration, A represents that part of the charm having the outline of a lamp-body; B, that part having the form of a chimney; C,

that part having the form of a shade; and D D 20 are the arms or wings, which are outlined, and have their surfaces treated to represent scrolls of leaves. For attaching the charm to a chain a ring, d, is provided; but a bail of any preferred form may be pivoted to the arms D D 25 for such purpose, if preferred.

What I claim, and desire to secure by Letters Patent, is—

The design for a pendent charm for chains, consisting of the parts A, B, and C, shaped as 30 set forth, and the arms or wings D D in the form of scrolls of leaves, substantially as described and shown.

HERMAN T. REGNELL.
